RAIL FOR PRICE TAGS OR THE LIKE

David J. Greiling, Kendallville, Ind., assignor to
McCrory Refrigerator Company, Kendallville,
Ind., a corporation of Indiana

Application May 22, 1950, Serial No. 10,078

Term of patent 3½ years

(Cl. D54—2)

To all whom it may concern:

Be it known that I, David J. Greiling, a citizen of the United States and resident of Kendallville, in the county of Noble and State of Indiana, have invented a new, original, and ornamental Design for a Rail for Price Tags or the like, of which the following is a specification, reference being had to the accompanying drawing, forming a part thereof.

In the drawing, Fig. 1 is a top edge view of a rail for price tags or the like, showing my new design; Fig. 2 is a front face view thereof, and Fig. 3 is a cross-section on the line 3—3 in Fig. 1.

The rear of the instant article is substantially plain.

I claim:

The ornamental design for a rail for price tags or the like, substantially as shown and described.
DAVID J. GREILING.
